REVERSIBLE ENGINE STARTER GEARING

John J. Sabatini, Horseheads, N.Y., assignor to Bendix Aviation Corporation, Elmira Heights, N.Y., a corporation of Delaware

Application October 23, 1958, Serial No. 769,245

8 Claims. (Cl. 74—9)

The present invention relates to reversible engine starter gearing and more particularly to a drive of the automatic traversing type which is operable in either direction of rotation.

The rapid growth of outboard marine engines both in quantity and size has caused a demand for suitable electrical starting equipment. In order to obtain maximum power per pound weight of the unit, it is common to use two-cycle engines and since such engines are generally reversible in operation, a further economy has been sought by taking advantage of this feature to eliminate the necessity for reversible gearing to the propeller to assist in maneuvering. This, of course, requires starting mechanism adapted to initiate rotation of the engine in either direction.

It is an object of the present invention to provide a novel reversible engine starter drive which is effective and reliable in operation and simple and economical in construction.

It is another object to provide such a device which embodies a pin and slot connection for traversing a pinion into and out of mesh with an engine gear and for rotating the pinion to crank the engine.

It is another object to provide such a device which is substantially a self-contained unit readily assembled on the shaft of a starter motor.

It is another object to provide such a device incorporating means which is effective in either direction of rotation for cushioning the initial operation of the drive.

It is another object to provide such a device having means for preventing the pinion from rebounding toward the engine gear when it is thrown out of mesh when the engine starts.

Further objects and advantages will be apparent from the following description taken in connection with the accompanying drawing in which:

Fig. 1 is a side elevation partly broken away and in section of a preferred embodiment of the invention showing the parts in normal or in idle position; and

Fig. 2 is a detail in side elevation of the flanged tubular traversing member.

In Fig. 1 of the drawing there is illustrated a power shaft 1 which is shown as the extended armature shaft of a reversible electric motor 2. A pinion 3 is slidably journaled on the shaft 1 for movement into and out of mesh with a gear 4 of the engine to be started. Means for moving the pinion 3 into mesh with the engine gear responsive to acceleration of the power shaft in either direction of rotation is provided comprising a barrel member 5 which is slidably journaled on the power shaft 1 and is provided with V-shaped teeth 6, arranged to cooperate with similar teeth 7 on the adjacent end of the pinion 3. The slope of the teeth 6, 7 is such that the pinion may overrun the barrel member 5 in either direction of rotation, but when the members are pressed together by the transmission of torque from the starting motor, the teeth transmit rotation to the pinion without slippage.

A tubular traversing and driving member 8 is slidably and rotatably mounted on the shaft 1 within the barrel member 5 and is formed with a flange 9 having radial projections 11 slidably mounted in axially extending slots 12 in the barrel to form a splined connection therebetween. A cylindrical block 13 of elastically deformable material is seated in the barrel member 5 against its terminal flange 14, and in engagement with the flange 9 of traversing member 8. The elastic member 13 is maintained under initial compression by a lock ring 15 which retains the traversing member 8 in the barrel 5.

A pin 16 is rigidly mounted in the power shaft 1 and the traversing member 8 is formed with a spiral slot 17 slidably receiving the projecting portion of said pin. The slot 17 is bent back on itself to provide a V-shaped conformation, the apex 18 of which receives the pin 16 when the drive is in idle position. The slot is arranged to run out at 19 in order to permit passage of the pin 16 when the drive is assembled on the shaft.

Means for normally maintaining the drive in idle position is provided comprising an abutment collar 21 fixedly located on the power shaft by means of a lock ring 22, and an anti-drift spring 23 located between the collar 21 and pinion 3. The collar and pinion are counterbored as indicated at 24 and 25 to receive the ends of the anti-drift spring and to house said spring and permit the pinion to abut against the collar 21 in order to define its meshed position.

In order to prevent any possibility of the pinion being thrown back toward the engine gear after being demeshed therefrom the angle between the arms of the V-shaped slot at its apex 18 is made in the neighborhood of a right angle. The rotation of the traversing member on the power shaft is thus arrested by engagement of the pin

30 16 against the opposing wall of the slot beyond said apex, which is substantially normal to the path of travel of the pin and consequently causes little or no tendency for the parts to rebound toward the engine gear. In operation, rotation of the power shaft 1 in either direction will cause 35 the pin 16 to move the traversing sleeve 8 to the right from its idle position carrying with it the barrel 5 and pinion 3, compressing the spring 23 until the pinion engages the abutment collar 21. Further rotation of the power shaft causes axial pressure to be exerted yieldably by the elastic 40 member 13, compressing the pinion between the toothed flange 14 and the abutment collar 21 whereby the pinion 45 is caused to rotate and crank the engine.

When the engine starts, the acceleration of the pinion 3 by the engine gear is transmitted to the barrel member 5 causing it to be traversed back to idle position by the pin 16. The overrunning of the traversing sleeve on the shaft 1 is prevented by the engagement of the pin 16

50 against the side of the slot beyond the apex 18, which, as above pointed out, is substantially normal to the relative movement of the pin 16 in the slot during the demeshing movement. The pinion, however, is free to overrun although the teeth 6, 7 of the barrel and pinion are yieldably held in contact by the anti-drift spring 23.

Although but one form of the invention has been shown and described in detail, changes may be made in the design and arrangement of the parts without departing from the spirit of the invention.

I claim:

65 1. In a reversible engine starter drive a power shaft, a pinion slidably journaled thereon for movement into and out of mesh with a gear of an engine to be started, a barrel member having a clutch connection to the pinion, a tubular member slidably journaled on the power shaft having a splined connection with said barrel and having a V-shaped spiral slot, a pin rigidly mounted in the shaft traversing said slot, and means for yieldingly trans-

mitting the longitudinal movement of the tubular member to the barrel.

2. An engine starter drive as set forth in claim 1 in which the apex of the V-shaped slot is pointed toward the pinion, and defines the idle position of the tubular member on said pin, including further an abutment on the power shaft defining the operative position of the pinion.

3. An engine starter drive as set forth in claim 2 including a compression spring between said abutment and the pinion urging the pinion and barrel assembly in the direction to hold the apex of the V-shaped slot against said pin.

4. An engine starter as set forth in claim 1 in which one arm of the V-shaped slot is extended to run out of the tubular member to permit entry of said pin.

5. An engine starter drive as set forth in claim 1 in which the clutch connection to the pinion comprises means for transmitting rotation in either direction from the barrel member to the pinion when the pinion is in meshed position, but is arranged to overrun in either direction when the pinion is in idle position.

6. An engine starter drive as set forth in claim 1 in which the clutch connection from the barrel member to the pinion comprises cooperating obtuse angled V-shaped teeth on the engaging surfaces thereof.

7. An engine starter drive as set forth in claim 1 including further an abutment fixed on the power shaft in the path of the pinion to define its meshed position, and in which the clutch connection from the barrel to the pinion is in the form of a dental clutch adapted to overrun in either direction, and said yielding means is in the form of a cylinder of elastically deformable material in the barrel, said tubular member having a flange splined in the barrel and arranged to compress said cylinder and thereby cause the barrel to press the pinion against said abutment and transmit rotation thereto in response to acceleration of the power shaft in either direction.

8. An engine starter drive as set forth in claim 7 including further a compression spring between the pinion and said abutment urging the pinion toward idle position, and maintaining the pinion in engagement with the barrel member.
